UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

PRINTING-TELEGRAPH SYSTEM.

Application filed March 25, 1918. Serial No. 224,295.

To all whom it may concern:

Be it known that I, ALBEN E. LUNDELL, a citizen of the United States, residing at New York, in the county of Bronx, State of New York, have invented certain new and useful Improvements in Printing-Telegraph Systems, of which the following is a full, clear, concise, and exact description.

This invention relates to printing telegraph systems and has for its object to provide a system in which a large number of mechanisms may be actuated selectively although the line transmits only a small number of impulses per signal.

The invention comprises a system in which there is a transmitting and a receiving station connected by two or more line wires. At the transmitting end, means are provided to transmit impulses over the line. The transmitters are so constructed that the periods of current and no-current in the various lines during the transmission of a given signal overlap each other in a manner determined by the particular signal transmitter operated. At the receiving end of each line wire, is a line relay which controls contacts connected to a plurality of circuits in which are selecting relays. The selecting relays are energized through interdependent circuits and are adapted successively to close a plurality of break points so that the ultimate effect of the operation of the selecting relays by the particular signal combination is that a circuit is closed to energize a desired mechanism in the receiver. If, for example, it is necessary to operate a certain number of relays to close a desired circuit, these relays are energized and locked up, one after another, due to the sequential and variable operation of the line relay contact members.

In order to cause the periods of current and no-current on the various lines to overlap, one line with respect to another line, this system provides means for sending long and short impulses of unidirectional currents, impressed on each line in various combinations. In addition, means are provided so that the beginning or ending of the impression of a combination on one line may, or may not coincide in point of time with the beginning or ending of the impression of the same or another combination on another line, the various combinations of impulses, however, impressed on the lines during a given interval

of time, resulting in the operation of a desired mechanism.

As a result, therefore, of this overlap of line signals, and the interdependence of the selecting relay circuits, the particular effect of the operation of any one of said line relays depends upon the nature of the action of the other line relays during the same interval of time.

The invention is illustrated in the drawings, of which Figs. 1 and 2 represent the diagrammatic arrangement of the circuits and apparatus employed in this system, the circuit wires of Fig. 1 continuing to the right into Fig. 2. That part of Fig. 1 to the left of the dot and dash line represents the transmitting end of the system and that part to the right of said line a portion of the receiving end of the system. Fig. 3 is a table, the respective columns of which represent—

Column 1—Mechanism to be actuated. 75

Column 2—Selecting relays to be ultimately locked up.

Column 3—Selecting relays not to be locked up.

Column 4—Signals in upper line; signals 80 in lower line.

Column 5—Order of operation of relays to lock up those in column 2.

As illustrated, the system comprises two line wires 1 and 2, the circuits of which, at 85 the transmitting end, are closed by switches 4 and 3, operated respectively by cams 6 and 5. These cams are operated simultaneously by a key 7. The transmitter comprises a plurality of pairs of such cams operated by 90 keys. Each pair of cams is adapted to transmit a different signal to the line. The surfaces of these cams are cut so as to operate their respective switches to transmit the desired combinations of impulses over the lines. 95 The cuttings on one disk are angularly placed, with respect to those on the other disk, so that the signals are impressed on the lines in their proper relative sequence. The cuttings shown are designed to impress a signal 100 on the line which will effect the actuation of mechanism 244. This signal on each line comprises two long impulses with a short one intervening, these combinations being impressed on their respective lines in the 105 sequential relation shown in Fig. 3. A pair of cams is provided for each character key.

At the other end of line wires 1 and 2 are

line relays 10 and 11, adapted, when energized, to operate armatures 8 and 9 which vibrate between contacts interconnected to a plurality of circuits containing selecting relays, and ultimately leading to a plurality of mechanisms to be actuated, of which 225, 232, 244, and 256 are indicated.

The relation of the various circuits and relays will best be comprehended by a description of the operation of the device. We will assume that it is desired to actuate mechanism 244, which operation requires the transmission of certain combinations of impulses over the line wires. The particular combination desired is shown in Fig. 3 and is cut out on the cams shown in Fig. 1. This signal is composed of two long impulses with an intervening short impulse impressed on each line wire, and, as shown in Fig. 3, the combination is impressed on line 2 first, closely followed by its impression on line 1.

On Figs. 1 and 2, the circuit for mechanism 244, which it is desired to close, is indicated by heavy lines merely for the purpose of facilitating the inspection of this circuit during the description. It extends as follows:—from ground through lower armature and back contact of relay S, through lower armature and back contact of relay M, through upper armature and front contact of relay L, through upper armature and back contact of relay K, through upper armature and front contact of relay N, through upper armature and front contact of relay C', through upper armature and front contact of relay G', through lower armature and back contact of relay 75, through mechanism 244, through lower armature and back contact of relay 76, to battery. Since the circuits on the drawings are shown in their normal position, it is evident that, to close the circuit just described, the relays L, N, C' and G' must be looked up. The manner in which this is accomplished is as follows:—As key 7 is depressed, cam 5 closes its switch 3 to impress a long impulse on the line 2 and later during the maintenance of which, switch 4 is closed to impress a similar impulse on line 1. This long impulse on line 2 energizes line relay 11 which pulls up and energizes relays T and 30, through a back contact of armature 8, the armature 8 at this time being in a retracted position. However, immediately thereafter, and while the armature of relay 11 is still pulled up, a long pulse is impressed on line 1 which causes the armature of relay 10 to pull up and take battery off relays T and 30 and energizes relay Y over the following circuit:—battery, upper armature and front contact of relay 10, relay Y, upper armature and back contact of relay S, front contact and armature of relay 11 to ground. Relay Y locks up through its lower armature and contact,

winding of relay X to wire 12, upper armature and contact of relay KD to battery. Relay KD is a clear-out relay which, through the battery just mentioned, controls a holding circuit for certain relays, until it in turn is energized by the action of an actuating magnet PM which will be hereinafter described. The next change which occurs in the system is the breaking of the circuit of wire 2 for an instant. This break causes the armature of relay 11 to retract, putting battery on relay R over the following circuit: ground, armature and back contact of relay 11, winding of relay R, front contact and upper armature of relay 10 to battery. Referring to Fig. 3, it will be noted that this break in line 2 is of very short duration, but of sufficient length of time for relay R to cause relay B to be energized over the following circuit: battery, lower armature and front contact of relay R, upper armature and front contact of relay Y (which is locked up through relay KD), lower armature and back contact of relay D, winding of relay B to ground. Relays B and D lock up over the following circuit: ground, winding, front contact and inner armature of relay B, winding of relay D', winding of relay D, wire 13, wire 12, to battery at relay KD. Line wire 2 is immediately closed to take off battery at relay R. Relay D being locked up, puts battery on relay L over the following circuit: battery, upper armature, front contact of relay D, winding of relay L, back contact and lower armature of relay G to ground. Line circuit 2 is again broken momentarily, the effect of which is to put battery on relay F over the following circuit: battery, lower armature and front contact of relay R, upper armature and front contact of relay Y (which is locked up), lower armature and front contact of relay D (which is locked up), upper armature and back contact of relay H, winding of relay F to ground. Line 2 is closed again, pulling up relay 11, thereby deenergizing relay R which removes the battery at R from the circuit of relay F, whereupon relays F and H, having previously pulled up, lock up over the following circuit: ground, winding of relay F, lower armature and front contact of said relay, winding of relay H, wire 13, wire 12, to battery at KD. When relay H locks up it puts battery on relay N over the following circuit: battery, lower armature and a front contact of relay H, wire 14, winding of relay N, back contact and upper armature of relay C, to ground. Relay N locks up through its own winding and lower armature, wire 17, wire 13, wire 12 to battery at KD. Relay P is likewise energized, when relay H locks up, over the following circuit: battery, lower armature and the other front contact of relay H, winding of relay P, wire 15 to ground at lower armature of relay G. 130

Relays P and P' lock over the following circuit: ground, upper armature and front contact of relay P, winding of relay P', wires 16, 17, 13 and 12 to battery at KD. It is to be borne in mind that the relay 10 has been maintained energized all this time, during the above described operation of relay 11. Relay 11 now remains energized while the following operations occur, due to the action of relay 10.

Line circuit 1 is broken for an instant, causing armature 8 to retract, energizing relay T over the following circuit: battery, armature and back contact of relay 10, relay 30, relay T, front contact and armature of relay 11 to ground. Relay A is thereby energized over the following circuit: from ground, lower armature and contact of relay T, upper armature and front contact of relay X (which has been previously locked up as described), lower armature and back contact of relay C, winding of relay A, wires 16, 17, 13 and 12, to battery at KD. When relay A energizes, a circuit is prepared to lock up 25 relays A and C, through upper armature and front contact of relay A, winding of relay C to ground. Relay 10 pulls up for an instant, deenergizing relay T, thereby removing ground at relay T, and consequently 30 the short on relay C which thereupon pulls up and locks up, as above noted, putting ground on relay C through the upper armature of relay C. Relay 10 breaks again, energizing relay T. This closes a circuit for 35 relay E as follows: ground, lower armature and front contact of relay T, upper armature and front contact of relay X, lower armature and front contact of relay C, upper armature and back contact of relay G, 40 winding of relay E, wires 16, 17, 13 and 12 to battery at KD. When E energizes, a circuit is prepared to lock up E and G through lower armature of E to ground through G. Relay 10 pulls up, removing the short 45 circuit from relay E at T. Therefore, relay E locks up over the following circuit: ground, winding of relay G, lower armature and front contact of relay E, wires 16, 17, 13 and 12, to battery at KD. Relay G pulls up 50 and closes the following circuit: ground, lower armature and a front contact of relay G, windings of relays G', G'', G''' to battery. It will be noted that the breaks in the circuit to mechanism 244 have all been closed 55 and that those relays, the energization of which controls these breaks, are locked up to battery at KD. Relay 11 breaks, after which relay 10 breaks. The only operation which remains to be performed is that of 60 actuating the selected mechanism, which is accomplished in the manner hereinafter described. Actuating magnet PM is provided, the windings of which are connected to the back contacts of the line relay armatures 8 65 and 9 so that whenever both of these armatures

are on their back contacts at the same instant the magnet PM is actuated. The character and sequence of the combinations of impulses is so arranged, however, that this does not occur until the end of the signal. The fact that one line relay is always energized while the other is breaking, therefore, not only promotes the extension of any given circuit but prevents the effective actuation of magnet PM. When both armatures 70 8 and 9 are retracted the following circuit is closed: from battery, armature and a back contact of relay 10, winding of actuator magnet PM, front contact and lower armature of relay X (which is locked), wire 18, 80 back contact and armature of relay 11, to ground. This magnet PM is then actuated and cooperates with the selected mechanism 244 to print a character or to perform any of the other functions incident to printing 85 and at the same time closes an operating circuit for clear-out relay KD which opens the holding circuits as previously described.

For the purpose of setting forth the operation of certain other relays, the operation of the device to select mechanism 256 will next be described. The selection of this mechanism requires the impression on the lines of signal combinations of the character and in the order shown in Fig. 3. Reading 90 from the right hand of Fig. 2 to the left through Fig. 1, the circuit which must be established to select mechanism 256 is as follows: from battery, through upper armature 95 and front contact of relay 96, mechanism 100 256, front contact and upper armature of relay 95, front contact and inner armature of relay G''', front contact and outer upper armature of relay P', front contact and lower armature of relay I', front contact 105 and upper armature of relay K, front contact and upper armature of relay L, back contact and lower armature of relay M, back contact and lower armature of relay S to ground. It will be seen that to close said circuit, the break points controlled by the following relays must be closed: 95, 96, G''', 110 P', K, and L.

The relay 10 is operated, energizing relay R over the following circuit: battery, upper 115 armature and front contact of relay 10, winding of relay R, armature 9 to ground. Relay 31 is energized from battery, lower armature of relay R, upper armature and back contact of relay Y, winding of relay 31, 120 a winding of relay S to ground. Relay 31, thereupon closes the following circuit from ground and lower armature of relay 31 to wire 22, wire 23, through relays 26, 36, 46, 56, 66, 76, 86, 96, 106, 116, to battery 24. Relay 31 locks up through its lower armature, 125 wires 13 and 12, to battery at relay KD.

Relay 11 is then energized, closing a circuit through relay Y as follows: ground, armature 9, and front contact of relay 11, 130

upper armature of relay S, winding of relay Y, to armature 8 and battery. Y locks up through X as follows: lower armature and winding of Y, winding of X, wire 12 to battery at relay KD. X then pulls up. Relay 10 then breaks for an instant, putting battery on T as follows: battery, armature 8, relay 30, relay T, front contact and armature of relay 11 to ground. T closes a circuit for relay A as follows: lower armature of T, outer armature and front contact of relay X, lower armature and back contact of relay C, relay A, wires 16, 17, 13 and 12 to battery at relay KD. A pulls up and prepares a circuit for the operation of relay C, which, however, does not operate at this time because it is short-circuited at the lower contact of relay T. Immediately thereafter, however, line relay 10 pulls up opening the circuit of T at its back contact, and locking up relays C and A through the following circuits: ground at C, winding of C, upper armature of A, through A, and so on to battery at KD as before. When C energizes it pulls up both its armatures. Through its lower armature it prepares a circuit for relay E. Through one of its front contacts and upper armature it actuates relay I over the following circuit: ground, upper armature of C and front contact, winding of I, back contact and upper armature of relay D to battery. Relay I and I' then lock up over the following circuit: ground, lower armature of I, winding of I, to I', wires 16, 17, 13 and 12 to battery at relay KD. At another front contact, C closes the following circuit: ground, upper armature and front contact of C, wire 19, wire 20, winding of K to lower armature, back contact of H, to battery. K locks up with ground through its lower armature, through K, to wires 16, 17, 13 and 12 to battery at KD. Relay C through wire 19 also locks up relay C'. Relay 11 next deenergizes, causing armature 9 to retract for an instant, during which time relay R is energized over the following circuit: ground, armature 9 and back contact of relay 11, relay R, front contact and armature of relay 10 to battery. Relay B energizes over the following circuit: battery, lower armature of R, upper armature and front contact of Y, lower armature and back contact of D, relay B to ground. Relay 11 pulls up, deenergizing relay R. Relay B will be locked up from ground, relay B, upper armature of B, relay D', relay D, to wire 13, to battery at relay KD. D pulls up and energizes L over the following circuit: battery, upper armature and front contact of D, relay L, to ground on lower armature of G. L locks up through its lower armature to wire 13 to battery at relay KD. Relay 11 breaks again and F is energized over the follow-

ing circuit: battery, lower armature of R, upper armature and front contact of Y, lower armature and front contact of D, upper armature and back contact of H to F and ground. When F pulls up, a circuit is prepared, which, when R is subsequently deenergized, becomes effective and locks F as follows: ground, winding of F, lower armature of F, relay H, to wire 13 and battery at relay KD. 75

Relay 10 next drops off for an instant, energizing T, which causes the energization of E over the following circuit: ground, lower armature of T, outer armature and front contact of X, lower armature and front contact of C, upper armature and back contact of G, relay E, wires 16, 17, 13 and 12, to battery at relay KD. When E pulls up a circuit containing ground is prepared for E to lock up, but this does not become effective until relay 10 pulls up, which it does immediately, thereby deenergizing T and removing the short circuit which allows E to lock up over the following circuit: ground, relay G, relay E, to wires 16, 17, to battery at KD as before. G pulls up and put ground and battery on G', G'', and G''', through the lower armature of G. 80

Relay 10 deenergizes, relay 11 remaining energized, causing the energization of relay 30, over the following circuit: battery armature 8, relay 30, relay T, upper armature of T, lower armature of KD to ground. Relay 30, therefore, remains locked up until relay KD breaks the circuit of relay 30 at its lower armature. Relay 30, operating, puts ground on 37, and completes an operating circuit to battery 39 for relays 25, 35, 45, 55, 65, 75, 85, 95, 105, 115. At this time relays 95 and 96 as above described energized and locked up, thereby completing the circuit to the selected mechanism 256. Immediately thereafter relay 11 is deenergized, completing the following circuit: from battery at armature 8, through PM, to front contact and inner armature of X to back contact and armature 9 of relay 11 to ground. Relay PM therefore energizes and cooperates with the desired mechanism to perform their functions and at the same time through its armature energizes KD to break circuit of battery at KD and at its lower armature the holding circuit for relay 30 just described, thus clearing out all the apparatus, which returns to normal position. 110 105 120

The selection of any other mechanism is merely dependent upon the character of the impulses sent over the line and of the relative operation of armatures 8 and 9 in response to the line impulses through the relays 10 and 11. 125

What is claimed is:

1. In a printing telegraph system, a pair of line conductors, means for impressing on said line conductors various combinations of 130

message impulses, a receiver connected with said line conductors comprising a plurality of printing magnets selectively responsive to said impulses, a single relay in each of the line conductors responsive to the operation of said means and dependent upon the respective order and relative duration of the impulses in the respective lines for selecting one of said printing magnets, and an actuating magnet energized only when said line relays are deenergized at the end of the signal combination for causing the operation of the selected printing magnet.

2. In a printing telegraph system, a pair of lines, means for transmitting combinations of impulses over said lines, a receiver associated with said lines comprising a plurality of printing magnets, a plurality of interdependent electromagnetic devices, circuit connections completed by said devices for actuating said printing magnets selectively, a single relay associated with said lines and actuated by said combinations of impulses to operate said selective devices, the selective devices actuated by the operation of one of said line relays during a given interval of time being dependent upon the character of the actuation of the other line relays during the same interval of time.

3. In a printing telegraph system, a pair of line conductors, transmitting means for impressing message impulses on said line conductors, a single relay in each of said

line conductors responsive to the operation of the transmitting means in accordance with the respective order and relative duration of the impulses in the two line conductors, a receiver comprising a plurality of printing magnets and a plurality of relays intermediate said line relays and energized upon the operation thereof in a predetermined order for controlling the energization of one of said printing magnets.

4. In a printing telegraph system, a plurality of printing magnets to be selected, a selecting circuit for each of said printing magnets, said circuits containing a plurality of break-points, a plurality of selecting relays for closing said break-points, a plurality of lines, means for transmitting combinations of impulses over said lines, a line relay in each of said lines, an armature controlled by each of said line relays, said armatures being connected with the circuits of said selected relay and operated by such combinations of impulses to close the break-points in a circuit leading to the printing magnet selected, an actuating magnet for said printing magnets energized only when the armatures of said line relays are all retracted at the end of the signal combination.

In witness whereof, I hereunto subscribe my name this 19th day of March A. D., 1918.

ALBEN E. LUNDELL.
